UNITED STATES PATENT OFFICE.

GEORGE R. DAVIS, OF SEATTLE, WASHINGTON.

SHOE CONSTRUCTION.

1,058,561.

Specification of Letters Patent.

Patented Apr. 8, 1913.

Application filed August 15, 1912. Serial No. 715,267.

To all whom it may concern:

Be it known that I, GEORGE R. DAVIS, citizen of the United States, residing at Seattle, in the county of King and State of Washington, have invented certain new and useful Improvements in Shoe Construction; and I do hereby declare the following to be a full, clear, and exact description of the invention, such as will enable others skilled 10 in the art to which it appertains to make and use the same.

This invention relates to shoes having improved insoles for the purpose of supporting the instep, and has as an object to provide a shoe having an insole with an instep brace and an instep support formed integral therewith.

A further object of the invention is to provide means for holding the instep brace and support in normal position, the means being secured to the shoe in such a way as to leave a water-tight insole.

A still further object of the invention is to provide means for supporting the instep brace and support which will insure the close contact of the instep brace and support with the instep of the foot, to prevent the slipping of the shoe upon the foot.

In the drawings: Figure 1 is a side elevation of the insole equipped with the present invention. Fig. 2 is a top plan view of the insole shown in Fig. 1. Fig. 3 is a transverse vertical section through the instep of a shoe constructed according to the present invention.

Like reference characters designate corresponding parts throughout the several views.

The broad scope of this invention aims to provide a shoe constructed with an insole having an instep brace, and an instep support held in normal position by strips located between the upper and the lining of the shoe secured to the insole, and laced with the lacing of the shoe. It will be apparent as the description proceeds that this type of shoe can be used on either the Blucher or laced style or any style of shoe which is laced to the foot. It will also be obvious 50 that the construction could be adapted to sandals and other forms of shoes, not ordinarily provided with vamps.

Referring to the drawings, Fig. 3 particularly, it will be seen that the insole 1 is provided with a skived instep support 2 upon one side thereof, and a brace 3 upon

the opposite side. The insole 1 is made of leather and may have the support 2 and brace 3 formed integral therewith or secured thereto in any suitable manner.

The instep brace 3 may be made to conform to any shape of foot and if not formed integral with the sole may be made of any flexible material which will retain a given shape. The object of the support 2 is to prevent the foot from slipping transversely due to the slope of the brace 3. The ordinary insole plate for bracing the same is shown at 4, the same being formed of metal and forming no part of the present invention. The underside of the insole 1 is provided with a channel 5, which defines a rib 6 which is continuous, extends around the sole of the instep as shown in Fig. 1, and has its two ends terminating in the heel of the instep. The rib 6 is provided with suitable punctures for receiving the thread which secures the lining 7 and the upper 8 to the shoe.

The lining and upper of this shoe are formed as in ordinary shoes, but there is inserted between the lining and the upper a pair of strips 9, one secured to the insole at a point opposite brace 3, and the other secured opposite to the instep support 2. In order to secure these strips 9 to the shoe, the thread is passed through a suitable welt, through the upper 8, through each strip 9, the lining 7, and through the punctures in the rib 6, this general process being the same as carried out in ordinary shoes. The upper ends of the strips 9 are provided with suitable holes 11 which are designed to receive the lace of the shoe. To complete this part of the shoe it is merely necessary to sew the outer sole to the welt 10.

When it is desired to make use of the strips 9, it is merely necessary to put the shoe upon the foot, to pass the lacing of the shoe through holes 11, and draw the lacing 100 tightly through the holes 11, whereby the strips 9 are bound tightly to the instep of the foot. The strips 9 are comparatively narrow, although not narrow enough to cause discomfort to the wearer, the object of 105 making the strips narrow being to prevent longitudinal slipping of the shoe upon the foot.

From the construction disclosed it will be apparent that the strips of leather or canvas 110 9 hold the shoe tightly to the foot, but cause no inconvenience because of the fact

that the ordinary lining 7 is interposed between the foot and the reinforcing strips. While acting as a reinforcement to the shoe, the strips 9 add very little extra weight to the shoe, and are designed to be held by the ordinary lacings, so that no inconvenience attends the use of a shoe constructed after the manner described.

What I claim is:

- 10 1. In a shoe having a lining and an upper, an insole, an instep support integral with the insole and straps secured to the opposite sides of the insole and located between the lining and the upper, said straps being adapted to be laced together.
2. In a shoe having a lining and an upper an insole, an instep support on one side of the insole, a brace on the other side of the insole, and straps secured to the insole under the support and brace and located between the lining and upper, said straps being adapted to be laced together.
3. In a shoe of the class described, an insole having an instep support formed on one side and a brace on the other side thereof, a rib formed on the insole extending beneath

the support and brace, and straps secured to the rib and provided with openings to receive a lacing.

15 4. In a shoe having a lining and an upper, 30 an insole, one side of which is turned up to form an instep support, a brace turned up from the other side of the insole, a rib formed on the insole at the base of the support and brace, and straps secured to the rib 35 and located between the lining and upper, and under the support and brace, the said straps being provided with holes adapted to receive a lace.

5. In a shoe having a lining and an upper, 40 an insole having an instep support and a brace, a rib formed on the lower side of the insole, straps located between the lining and the upper and adapted to be laced together, a welt and stitching securing the welt, up- 45 per, straps and lining to the rib.

In testimony whereof I affix my signature in presence of two witnesses.

GEORGE R. DAVIS.
